UNITED STATES PATENT OFFICE.

WILLIAM B. DURGIN, OF CONCORD, NEW HAMPSHIRE.

DESIGN FOR A HANDLE FOR SPOONS, FORKS, &c.

SPECIFICATION forming part of Design No. 20,644, dated March 31, 1891.

Application filed February 16, 1891. Serial No. 381,704. Term of patent 7 years.

To all whom it may concern:

Be it known that I, WILLIAM B. DURGIN, a citizen of the United States, residing at Concord, in the county of Merrimac and State 5 of New Hampshire, have invented and produced a new and original Design for the Handles of Spoons, Forks, &c., of which the following is a specification, reference being had to the accompanying drawing, in which the 10 figure represents a face view of a spoon having my new design produced on the handle thereof.

The leading feature of my design consists in the representation of the conventional figure of Rip Van Winkle, accompanied by symbols suggestive of the striking incidents in the legend in which he figures, the said symbols being in line with the main figure.

The letter *a* indicates the most prominent

feature, the conventional figure of Rip Van 20 Winkle, the same being represented in erect posture and as if carrying a gun. In line with the figure *a* are the ribbon figures *b*, the figure *c*, representing a barrel-head having a spigot therein, the figures *d*, representing tobacco- 25 pipes, the figures *e*, adjacent to the handles of said pipes and representing mugs, and the circular figures *f*, representing ten-pin balls. The various figures are in line with the main figure *a* and form in connection therewith my 30 new design.

I claim—

The design for the handles of spoons, forks, &c., as herein shown and described.

WILLIAM B. DURGIN.
